UNITED STATES PATENT OFFICE.

CHARLES E. BELDING, OF CANTON, OHIO.

EMBROIDERY-HOOP.

1,056,966.

Specification of Letters Patent. Patented Mar. 25, 1913.

Application filed November 15, 1911. Serial No. 660,512.

To all whom it may concern:

Be it known that I, CHARLES E. BELDING, a citizen of the United States, residing at Canton, in the county of Stark and State of Ohio, have invented certain new and useful 5 Improvements in Embroidery-Hoops, of which the following is a specification.

My invention relates to embroidery hoops composed of an inner hoop and an outer 10 ring, the outer ring adapted to be stretched over and upon the inner hoop for the purpose of clamping the fabric.

The objects of the present invention are, first, to provide means for clamping the 15 fabric in such a manner that fine and delicate fabric will be properly clamped and held taut; and second, to so clamp the fabric that it will not be injured; and third, to hold the fabric so that no slipping 20 of the fabric will occur during the time the fabric is being embroidered.

These objects together with other objects readily apparent to those skilled in the art I attain by the construction illustrated in 25 the accompanying drawings, although my invention may be embodied in a variety of other mechanical forms, the construction, illustrated being chosen by way of example.

In the accompanying drawing,—Figure 1 30 is a view showing the inner hoop and the outer band placed together in their normal position to clamp and hold the fabric. Fig. 2 is a similar view showing the inner hoop formed oval and the outer band located 35 upon the oval hoop. Fig. 3 is a view showing a portion of the outer band and its coupling device, said view showing a portion of the outer band in side elevation and a portion in section. Fig. 4 is a transverse 40 section on line 4—4, Fig. 1, and line 3—3, Fig. 2.

Similar numerals of reference indicate corresponding parts in all the figures of the drawing.

45 In the accompanying drawing, 1 represents a non-elastic or rigid hoop, and 2 the inner non-elastic hoop formed oval as in Fig. 2. The hoops 1 and 2 are of the same construction, except that in Fig. 1 the hoop 50 is circular and in Fig. 2 elliptical, otherwise they are the same. In use I prefer to form the hoops 1 and 2 of the same particular relative size so that the outer band can be placed upon either the round hoop or the 55 oval one as desired. It will be understood that the two hoops 1 and 2 when made of

the same relative size, have to do with one pre-determined size, say the circular hoop, six inches in diameter and the oval or elliptical hoop of the same relative size, but it 60 will be understood that different sizes of hoops both circular and elliptical may be made as for instance the circular hoop may be ten inches in diameter and the oval one of corresponding size so that one outer band 65 can be used for both circular and oval hoops; but it will be understood that the outer band should be of such a size that it will fit either a circular inner hoop or an elliptical one. The inner hoops being of the 70 same relative size whether elliptical or round. As shown the outer band is made up of the inner wire 3 around which wire is located the inner tube 4 and around which inner tube 4 is located the outer tube 5, the 75 purpose of providing two tubes is to form the outer band proper of such a size that it will properly clamp the fabric, but I do not desire to be confined specifically to two 80 tubes as it will be understood that the outer tube may be formed of the proper size and the wire 3 located through the outer tube. The only object designed to be accomplished is to provide an outer band that will be quite elastic and pliable and in order to accomplish this I prefer to use inner and outer tubes, thereby reducing the thickness 85 of the material. The tubes 4 and 5 are preferably formed of rubber or other yielding and pliable material, the material employed 90 being such that it will have the proper adhesiveness or hugging qualities to properly hug or clamp the fabric. The inner hoops 1 and 2 are provided with the groove 6, which groove is for the purpose of properly seating 95 the outer band so that it will not only clamp the fabric, but prevent the band from being accidentally removed when placed in position. The ends of the wire 3 are provided with the eyes 7, to which eyes are attached the 100 hooked ends of the spring 8, which spring is for the purpose of giving to the outer band the desired amount of elasticity so that the outer band can be easily placed upon and removed from the inner hoops 1 or 2 as desired, the tension of the spring being such that the outer band will snugly fit the surface of the groove or simply fit and press upon the fabric designed to be placed upon the inner hoop and outer band. 105 110

For the purpose of protecting the ends of the outer tube 5, said outer tube is provided

with the short metal sleeves 9, which metal sleeves also serve the purpose of covering the spring 8 and preventing the spring from coming in direct contact with the fabric.

5 The sleeves 9 are preferably provided with a series of annular grooves or ridges 10, which assist in firmly holding the sleeves 9 upon the ends of the outer band 5.

It will be understood that when the outer 10 band is placed upon the inner hoops 1 and 2 and when removed therefrom, a slight rolling action will be given to the outer band, owing to the elasticity and pliability of said outer band, thereby preventing any sliding 15 or slipping action upon the fabric, which sliding or slipping action has a tendency to injure the fabric, especially if the fabric is of a fine texture.

By forming the outer tube 5 hollow and 20 continuous and of sufficient length to be clamped upon the inner hoops 1 and 2, said tube being formed of elastic material is easily removed from the groove in the inner hoops, owing to the fact that a slight torsional movement or action is imparted to the outer tube for a portion of its length, thereby giving to said tube a partial rolling movement during the time it is removed or placed upon the inner hoops. This rolling

or torsional movement is only for a small 30 portion of the length of the tube and when the tube is seated in the groove or is freed from the inner hoops, said tube automatically assumes its normal position.

Having fully described my invention what 35 I claim as new and desire to secure by Letters Patent, is—

As an improved article of manufacture, an embroidery hoop comprising an inner rigid hoop having a groove upon its face, a flexible band formed of a length substantially equal to the length of the outer surface of the inner hoop, a hollow flexible tube located within the flexible band, a wire located within the hollow flexible tube and 40 concentric therewith, said outer band adapted to torsionally move upon the flexible tube, a spring located between the ends of the wire and a sleeve adapted to inclose said spring, substantially as and for the purpose 45 50 specified.

In testimony that I claim the above, I have hereunto subscribed my name in the presence of two witnesses.

CHARLES E. BELDING.
